TOOL FOR RUPTURING FILL CAPS

John J. Byrnes, Newark, N.J., assignor to
H. De Lancey Gregory, Newark, N.J.

Filed June 21, 1956, Ser. No. 592,910

2 Claims. (Cl. 30—91)

My invention relates to a tool for rupturing fill caps. In an underground installation of a fuel oil tank such, for example, as is used for supplying domestic or other oil burners, there is a fill pipe coupled at one end thereof to the tank. The fill pipe generally extends vertically upward from the tank to the surface above which may be a concrete or other finished surface over which pedestrians and traffic pass. The top end of the fill pipe is open for the entrance of fuel oil in filling the tank and is externally threaded for application thereto of an element identified as a fill cap. The conventional fill cap is of cast iron and is internally threaded for screwing down on and about the top or terminal end of the fill pipe and for receiving an externally threaded, brass lug or stopper. The latter closes the fill pipe and is unscrewed and removed from the fill cap only when the tank is to be replenished with fuel oil. After being applied to the open or terminal end of the fill pipe and screwed down tightly on the same, the fill cap is a permanent part of the installation and for all intents and purposes is integral with the threaded pipe end. In the course of time the brass stopper is unscrewed numerous times from the cast iron fill cap and is later put back and screwed down tight again, after a new supply of fuel oil has been poured down the fill pipe. The repeated unscrewing of and the subsequent screwing up tightly on the brass stopper has, in the past, partially stripped or otherwise damaged the cast iron threads of the fill cap to an extent making it necessary to remove the old fill cap and replace it with a new one. This trouble with the cast iron threads is enhanced by the fact that in most cases the associated brass stopper and cast iron fill cap are exposed to adverse weather conditions which in time cause some corrosion of the cast iron threads. It then becomes necessary to apply considerable counter-clockwise torque to the brass stopper in loosening and unscrewing the same from the cast iron fill cap. This can cause at least some slight distortion of one or more of the cast iron threads so that there is some difficulty in later screwing in the stopper. Thus, the stopper is forced, and the condition becomes progressively worse and so much so that in time the cast iron fill cap must be replaced.

Over the years, between the external, cast iron threads on the top or terminal end of the fill pipe and the internal, cast iron threads of the fill cap, there is sufficient corrosion to cause the fill caps, in effect, to become "frozen" to the pipe end. Therefore, in wrenching the old fill cap counterclockwise to "break" it loose and then to unscrew and remove it from the pipe end, frequently requires application of a considerable amount of counterclockwise torque to the fill cap, and so much so that one or more of the external cast iron threads on the fill pipe can be stripped or distorted. The excessive torque applied to the fill cap is also applied to each horizontal section of the fill pipe from its top, externally-threaded end down to its bottom end which is coupled to the tank. This can and has caused a rupture or other damage at the bottom coupling, and so much so that

2

there is either a complete break at this underground point or at least a sufficient crack or rupture to permit subsequent seepage of water into the tank. This condition requires excavation to expose the entire length of the fill pipe for replacement of the same and for any other repair work which might be found to be necessary.

In some installations where there is sufficient clearance at the fill cap, the concrete or other material immediately about the latter is removed and a heavy wrench, stone or other equivalent object is wedged and packed in, firmly against one side of the old fill cap. A sledge hammer or other heavy tool is then used to strike the other side of the fill cap until the latter is broken or cracked off. This method can cause damage in one or both of two ways, as follows: The external threads on the top end of the fill pipe can be distorted. A crack or rupture can occur at the bottom coupling or union to permit subsequent seepage of water into the tank.

With the foregoing in mind, it is an object of my invention to provide a tool for rupturing or cracking a fill cap out of its tight, threaded engagement with the externally-threaded end of a fill pipe, and to do this without necessitating any rotary movement whatsoever of the fill cap with respect to the threaded pipe end, or any hammering on the fill cap, as heretofore.

Other objects and advantages will hereinafter appear. For the purpose of illustrating my invention an embodiment thereof is shown in the drawings, wherein

Fig. 1 is an elevational view of the tool herein shown inserted into a fill cap and in position to rupture or crack the latter off the threaded end of a fill pipe, the fill cap and fill pipe being shown in longitudinal section;

Fig. 2 is a plan view of the tool shown in Fig. 1; Figs. 3 and 5 are detail, elevational views respectively, 35 of the handle part and the wedge part of the tool shown in Fig. 1;

Fig. 4 is a plan view of Fig. 5;

Fig. 6 is a section taken on line 6—6 in Fig. 1, one of the parts being shown in elevation;

Figs. 7 and 8 are sections taken, respectively, on lines 7—7 and 8—8 in Fig. 3;

Fig. 9 is an elevational view of the tool, looking toward the right in Fig. 1; and

Fig. 10 is an elevational view, partly broken away, of an auxiliary part.

The tool comprises a handle part 10 having a flat face 11 at the bottom end thereof; a wedge part 14 having a flat face 15 at an end thereof and a substantially straight knife edge 16 at its other end; and a pin, bolt, rivet or equivalent means 17 extending through similar and registering openings 18 and 19 in the handle and wedge parts at the respective flat faces 11 and 15 of these parts.

In the embodiment shown, bolt 17 at one end thereof has a head 20 and is threaded at its other end to receive a nut 21. The nut 21 is tightened sufficiently and locked in any suitable manner to hold parts 10 and 14 together with their respective flat faces 11 and 15 engaging, as more clearly shown in Fig. 6.

Bolt 17 connects parts 10 and 14 for rotary movement relatively with respect to each other about the axis of bolt 17, which axis is perpendicular to the flat faces 11 and 15.

Handle part 10 at its bottom end is provided with a knife edge 22 disposed on the side of the bolt axis opposite to that on which the straight, knife edge 16 is disposed. Knife 22 is on an arc or circumference about a center indicated at 22', this center being eccentric with respect to the axis 17' of bolt 17. The knife edge 22 is in a plane through knife edge 16 and perpendicular to the axis 17'.

Handle part 10 is provided with the surface 23. Wedge part 14 is provided with the surface 24. These surfaces

are complementary with respect to each other and engage, as shown in Fig. 1, to hold wedge part 14 at an angle of ninety degrees to the longitudinal axis of handle part 10 when the latter is held vertically. Knife edge 16 is then disposed vertically to permit insertion of wedge part 14 and the associated end of handle part 10 into the fill cap 25, as shown in Fig. 1.

Fill cap 25 is of a conventional construction. It is of cast iron, and is internally threaded at the bottom for screwing onto the top, externally-threaded end of a fill pipe 26.

From the top edge of surface 24, the surface 27 in line with edge 16 slopes upwardly at an angle of forty-five degrees, as shown in Figs. 1 and 5. This permits counterclockwise rotation of handle part 10 through about forty-five degrees, from the vertical position shown in Fig. 1. With handle part 10 vertically disposed, between any two substantially opposite points of the complementary knife edges 16 and 22 the distance is slightly less than the inside diameter of fill cap 25. As handle part 10 is rotated counterclockwise, the distance between two substantially opposite points on the knife edges 16 and 22 increases progressively and finally to an extent whereat such distance is sufficiently greater than the inside diameter of fill cap 25 to rupture or crack the latter out of its tight, threaded engagement with the externally-threaded end of fill pipe 26.

For the purpose of insuring that the tool is inserted the proper distance into fill cap 25, handle portion 10 is provided with a shoulder 28 which engages the fill cap and thus supports the tool, as shown in Fig. 1, with its knife edges 16 and 22 placed for the most effective action, i.e., with these edges, respectively, in position to cut into and press outwardly on the fill cap at diametrically opposite points of the latter. In other words, it will be seen that the surface portions or knife edges 16 and 22 are so disposed that during rupturing operation of the tool there is always the condition wherein at least one point of either one of the surface portions or knife edges 16 and 22 is, with at least one point of the other of such surface portions or edges, in a plane through and parallel to the axis 17'. With the leverage provided by handle part 10 and the sharp and disposition of knife edge 22 as disclosed, there is ample pressure to crack fill cap 25 or actually split the latter in two. If more leverage is required an extension 29 is placed on handle part 10 and fixed with respect thereto by a pin or bolt (not shown) inserted through the respective holes 30 and 31 through the two parts.

In addition to all the above, other disadvantages of the externally-threaded pipe end 26 and the fill cap 25 internally threaded at its lower end for screwing onto the former, are explained in my application Serial No. 591,978, filed June 18, 1956.

Important aspects of my invention as embodied in the novel construction disclosed and claimed herein and adapted specifically and exclusively for rupturing fill caps identified and described above, residue, first, in the provision of a tool heretofore non-existent and which, in operation, ruptures, breaks, or "cracks" a fill cap into at least two separable parts which then fall or drop out of threaded engagement with the externally-threaded fuel-intake end of a fill pipe without having caused any stripping or other distortion of the outside threads of the fill pipe and, also, without having caused any damage whatsoever to the installation of which the fill pipe is a part; and, second, in the provision of such a tool comprising the wedge part 14 and the handle part 10 pivotally connected, the shape or characteristics of these parts and their coordination and relation with respect to each other be-

ing such that upon a single and continuing rotary movement of the handle part 10 relatively with respect to the wedge part 14 and in one and the same direction about an axis such as that identified by the reference character 5 17', the fill cap 25 is ruptured, "cracked," or split into at least two separable parts. This manner or principle of operation, i.e., the actual rupturing or "cracking" of a fill cap into at least two separable parts, is entirely distinct from the cutting or shearing action, can-opener fashion, of tools proposed heretofore but adapted and intended for entirely different purposes such as the cutting of sheet metal flues or tubes out of boilers. An example of such a tool as the latter for cutting through material such as tube steel of approximately one-eighth inch 15 gauge, is disclosed in Patent No. 1,173,953 issued February 29, 1916 to Frederick A. Grier, Jr.

It will be understood that various modifications within the conception of those skilled in the art are possible without departing from the spirit of my invention or the 20 scope of the claims.

I claim as my invention:

1. In a tool of the character described for rupturing a fill cap, a handle part, a wedge part, means pivotally connecting one end of said wedge part to an end of said handle part thereby connecting said parts for rotary movement relatively with respect to each other about an axis, said wedge part at its other and free end having a substantially straight edge disposed on one side of said axis and in a plane substantially perpendicular to said axis, said handle part at said end thereof being provided with an edge disposed on the opposite side of said axis and on an arc about a point eccentric with respect to said axis and substantially in said plane, said edges when said parts are at a given angle with respect to each other 25 being disposed so that between any two substantially opposite points of said edges the distance is sufficiently less than the inside diameter of said cap to permit insertion of said wedge part and the associated end of said handle part into said cap and that upon said handle part being moved to change said angle substantially the distance between two substantially opposite points of said edges increases progressively during such change of said angle and finally to an extent whereat said distance is sufficiently greater than said diameter to cause rupturing of said cap.
2. In a tool of the character described for rupturing a fill cap, a handle part having a flat face at an end thereof, a wedge part having a flat face at an end thereof and a substantially straight edge at its other end, means extending through said parts at said flat faces thereof and holding said parts together with said faces engaging and connecting said parts for rotary movement relatively with respect to each other about an axis perpendicular to said faces, said handle part at said end thereof being provided with an edge disposed on the side of said axis 30 opposite to that on which said straight edge is disposed, said edge on said handle part being on an arc eccentric with respect to said axis and substantially in a plane through said straight edge and perpendicular to said axis, said parts being provided with surfaces engageable with each other and complementary with respect to each other 35 in the sense that upon engagement of said surfaces with each other said relative rotary movement is prevented in one direction when said straight edge is disposed substantially parallel to the longitudinal axis of said handle.
3. In a tool of the character described for rupturing a fill cap, a handle part having a flat face at an end thereof, a wedge part having a flat face at an end thereof and a substantially straight edge at its other end, means extending through said parts at said flat faces thereof and holding said parts together with said faces engaging and connecting said parts for rotary movement relatively with respect to each other about an axis perpendicular to said faces, said handle part at said end thereof being provided with an edge disposed on the side of said axis 40 opposite to that on which said straight edge is disposed, said edge on said handle part being on an arc eccentric with respect to said axis and substantially in a plane through said straight edge and perpendicular to said axis, said parts being provided with surfaces engageable with each other and complementary with respect to each other in the sense that upon engagement of said surfaces with each other said relative rotary movement is prevented in one direction when said straight edge is disposed substantially parallel to the longitudinal axis of said handle.
4. In a tool of the character described for rupturing a fill cap, a handle part having a flat face at an end thereof, a wedge part having a flat face at an end thereof and a substantially straight edge at its other end, means extending through said parts at said flat faces thereof and holding said parts together with said faces engaging and connecting said parts for rotary movement relatively with respect to each other about an axis perpendicular to said faces, said handle part at said end thereof being provided with an edge disposed on the side of said axis 45 opposite to that on which said straight edge is disposed, said edge on said handle part being on an arc eccentric with respect to said axis and substantially in a plane through said straight edge and perpendicular to said axis, said parts being provided with surfaces engageable with each other and complementary with respect to each other in the sense that upon engagement of said surfaces with each other said relative rotary movement is prevented in one direction when said straight edge is disposed substantially parallel to the longitudinal axis of said handle.
5. In a tool of the character described for rupturing a fill cap, a handle part having a flat face at an end thereof, a wedge part having a flat face at an end thereof and a substantially straight edge at its other end, means extending through said parts at said flat faces thereof and holding said parts together with said faces engaging and connecting said parts for rotary movement relatively with respect to each other about an axis perpendicular to said faces, said handle part at said end thereof being provided with an edge disposed on the side of said axis 50 opposite to that on which said straight edge is disposed, said edge on said handle part being on an arc eccentric with respect to said axis and substantially in a plane through said straight edge and perpendicular to said axis, said parts being provided with surfaces engageable with each other and complementary with respect to each other in the sense that upon engagement of said surfaces with each other said relative rotary movement is prevented in one direction when said straight edge is disposed substantially parallel to the longitudinal axis of said handle.
6. In a tool of the character described for rupturing a fill cap, a handle part having a flat face at an end thereof, a wedge part having a flat face at an end thereof and a substantially straight edge at its other end, means extending through said parts at said flat faces thereof and holding said parts together with said faces engaging and connecting said parts for rotary movement relatively with respect to each other about an axis perpendicular to said faces, said handle part at said end thereof being provided with an edge disposed on the side of said axis 55 opposite to that on which said straight edge is disposed, said edge on said handle part being on an arc eccentric with respect to said axis and substantially in a plane through said straight edge and perpendicular to said axis, said parts being provided with surfaces engageable with each other and complementary with respect to each other in the sense that upon engagement of said surfaces with each other said relative rotary movement is prevented in one direction when said straight edge is disposed substantially parallel to the longitudinal axis of said handle.
7. In a tool of the character described for rupturing a fill cap, a handle part having a flat face at an end thereof, a wedge part having a flat face at an end thereof and a substantially straight edge at its other end, means extending through said parts at said flat faces thereof and holding said parts together with said faces engaging and connecting said parts for rotary movement relatively with respect to each other about an axis perpendicular to said faces, said handle part at said end thereof being provided with an edge disposed on the side of said axis 60 opposite to that on which said straight edge is disposed, said edge on said handle part being on an arc eccentric with respect to said axis and substantially in a plane through said straight edge and perpendicular to said axis, said parts being provided with surfaces engageable with each other and complementary with respect to each other in the sense that upon engagement of said surfaces with each other said relative rotary movement is prevented in one direction when said straight edge is disposed substantially parallel to the longitudinal axis of said handle.
8. In a tool of the character described for rupturing a fill cap, a handle part having a flat face at an end thereof, a wedge part having a flat face at an end thereof and a substantially straight edge at its other end, means extending through said parts at said flat faces thereof and holding said parts together with said faces engaging and connecting said parts for rotary movement relatively with respect to each other about an axis perpendicular to said faces, said handle part at said end thereof being provided with an edge disposed on the side of said axis 65 opposite to that on which said straight edge is disposed, said edge on said handle part being on an arc eccentric with respect to said axis and substantially in a plane through said straight edge and perpendicular to said axis, said parts being provided with surfaces engageable with each other and complementary with respect to each other in the sense that upon engagement of said surfaces with each other said relative rotary movement is prevented in one direction when said straight edge is disposed substantially parallel to the longitudinal axis of said handle.
